COOLANT CIRCULATING SYSTEM

Paul F. Barker, Brighton, N. Y., assignor to
Gleason Works, Rochester, N. Y., a corporation
of New York

Application August 3, 1942, Serial No. 453,366

2 Claims. (Cl. 51—267)

The present invention relates to grinding machines and more particularly to the coolant-circulating systems of such machines.

In most grinding, especially in most gear grinding, it is the practice today to "wet-grind," that is, to supply a liquid coolant to the grinding wheel and work at their area of contact in order to cool the wheel and the work and to wash away the bits of metal, which are ground off the work, and the abrasive grits, that are worn off of the wheel, in the grinding operation. The coolant is usually pumped onto the wheel and work from a sump or tank mounted in the base of the grinding machine, and after use the coolant flows back to the sump for use again. Since the returning liquid is laden with particles of metal and abrasive, it is necessary to clean the coolant before it is used again, otherwise the bits of metal and abrasive will be pumped up onto the work again and may become wedged between the wheel and work, causing scratching of the work and rapid wear of the wheel.

Water or a suitable emulsion may be used as the coolant, but in recent years it has become more and more the practice to use oil for this purpose. Where water is employed as the coolant, it is usual to provide the sump or tank with two chambers, a settling chamber and a pump chamber, constructed in such way that the coolant will have to overflow from the settling chamber into the pump chamber. The settling chamber is made large enough to allow the particles of metal and abrasive to settle out of the coolant liquid into the bottom of the chamber. In some cases, also, a system of baffles is employed through which the coolant has to return to the pump chamber. These aid in the removal of the abrasive grits and metal particles from the coolant.

Where oil is used as a coolant, however, it has been found that neither the settling chamber, nor the baffle system, nor the two combined operate very satisfactorily. Because of the viscosity of the oil, the particles tend to remain in suspension and the finer particles especially do not settle out but are carried over into the pump chamber where they are returned suspended in the coolant to the wheel and the work. It has become the practice, therefore, to filter the cooling oil before using it again. The ordinary commercial filters are, however, expensive, and they are difficult to clean. Moreover, they have to be cleaned quite often because under the conditions encountered in a grinding operation, they load up quickly.

The primary object of the present invention is 55

to provide a coolant-circulating system, especially for use where oil is employed as the cooling medium, which will insure delivery of clean coolant to the wheel and the work.

5 Another object of the invention is to provide a filter unit for use in a coolant-circulating system that will be efficient, simple, and inexpensive, and, moreover, that will be easy and cheap to service.

10 Other objects of the invention will be apparent hereinafter from the specification and from the recital of the appended claims.

In the drawings:

15 Fig. 1 is the side elevation of a standard form of spiral bevel and hypoid pinion grinder on which the coolant-circulating system and filter unit of the present invention is employed;

Fig. 2 is a plan view of the principal parts of 20 the coolant-circulating system, including the filter unit; and

Fig. 3 is a transverse sectional view through these parts.

In the coolant-circulating system of the present invention, the coolant is pumped from the sump 25 through a filter unit and thence through suitable conduits to the wheel and work, and after use, the coolant flows back into the sump whence it is pumped again through the system. The filter unit consists simply of a pail partially filled 30 with small rhomboidal or lozenge-shaped cast iron pieces or with crushed stone. As the coolant is pumped through the filter unit, the chips and abrasive grits are caught and removed. The use of crushed stone as the filtering medium is 35 preferred. In fact, the discovery that such a material may be employed as a filtering medium in the coolant-circulating system of a grinding machine is one of the features of the present invention. Crushed stone can be obtained readily 40 almost anywhere and it is so cheap that it can be thrown away after use. Cast iron pieces on the other hand are more expensive, and they are impractical to clean. Moreover, if the quantity of stone used warrants it, the stone can be 45 cleaned in an incinerator without damage, whereas the heat required to burn off the chips and grits would melt or fuse cast iron pieces.

While the invention may be applied to any type of grinding machine, it is shown in the drawings 50 in use on a spiral bevel and hypoid pinion grinder of the type illustrated in the patent of Ernest Wildhaber, No. 2,252,743, of August 19, 1941. Grinding on this machine is effected by a rotary annular grinding wheel, such as designated at W in Fig. 1, and the work piece is a spiral bevel

or hypoid pinion, such as denoted at **P** in Fig. 1, the side surfaces of whose teeth are to be ground by the wheel. A suitable guard **10** is provided to enclose the wheel, and coolant is supplied to the wheel and work at the area of their engagement through a nozzle **11** which is suitably mounted in the guard **10**. The coolant is pumped to the nozzle **11** from a tank, which is designated as a whole at **12**, and which is removably mounted in the base **14** of the machine.

The tank is divided into two chambers. One of these chambers, which is denoted at **15**, contains the filter unit. It is square shaped and is formed in one corner of the tank. It is separated from the other chamber, which is denoted at **16**, by the partition walls **17** and **18**. The chamber **16** is L-shaped and forms the sump chamber proper. The coolant falling from the guard **10**, and draining back to the tank, after use, flows into the sump chamber **16** through the rectangular opening **20** in the top wall of this chamber. The used coolant is conducted to the sump opening **20** through a suitable conduit (not shown) which may be in the form of piping, or a drain trough, or the like.

The filter unit is mounted in the chamber **15**. The filter unit comprises a pail **25** which has apertures **26** in its bottom and which is partially filled with crushed stone or with metal pieces **27**. The pail is flanged at its top and depends through a circular opening formed in the top wall **28** of the chamber **15**. The flanged rim of the pail seats on the surrounding part of the top wall **28** of the chamber **15** and the pail is thus suspended in the chamber.

The opening in the top wall **28** is closed by a cover plate **30** which is hinged on the top wall **28** by means of the hinge pin **31**. The cover plate may be clamped down to seal it against leakage by a clamping bar **32** and a clamping screw **33**. The clamp bar is pivoted at one end on a pin **34** which is mounted in the plate **28** and at its opposite end it is notched to engage under the head of a pin **35** which is also secured in the plate **28**. A bail **36** is provided for the pail so that it can be lifted out of the chamber **15** to clean or remove the stones **27**.

The coolant is pumped from the sump chamber **16** by a pump of any suitable construction such as a centrifugal pump shown at **40** in the drawings. The coolant is drawn into the pump through the duct **41**. From the pump **40**, the coolant is pumped through the piping **42** into a duct **43** that may be formed by an angular piece of sheet metal which is secured to the side wall **17** and top wall **28** of the chamber **15**. The duct **43** communicates through an opening **44** in the top wall **28** with a duct **45** that is formed in the cover plate **30**. This duct **45** conveys the oil to the pail **25**, and the pump pressure forces the oil through the filter pieces **27** into the chamber **15** from whence the pressure forces it into the pipe **47**. This pipe is secured in an opening in the top wall **28** of the chamber **15**. There are two pipes **48** and **49**, respectively, connected to the pipe **47**. The pipe **48** communicates with the nozzle **11** and supplies the coolant to the area of contact of the wheel and the work. The pipe **49** is an overflow pipe and preferably conducts coolant to the drain trough or piping through which the coolant returns to the sump chamber after use. The coolant flowing through the pipe **49** helps wash the grit and chips down into the sump and keep the trough or conduit clean.

There is a hand operated valve **51** mounted in the pipe **47** to control the flow of liquid between the pipe **47** and the pipe **49**. The pump pressure is greater than that required to force the necessary quantity of coolant to the area of engagement of the wheel and the work, and the excess liquid flows through the pipe **49** to the sump. Through continued use, the stones **27** pick up more and more chips and grits and the interstices between the stones become gradually clogged up so that more and more pressure is required to force the dirty oil through these filter pieces. Thus the amount of pressure for carrying the coolant to the point of operation gradually decreases with use of a given charge of the filter unit, so that it is necessary for the operator from time to time to adjust the valve **51** to decrease the flow between the pipes **47** and **49** and thereby keep up the necessary pressure in the pipe **48**. This is the purpose of the valve **51**.

When the filter unit becomes so clogged that it is no longer usable, a pail **25** can be removed from the chamber **15** by opening the cover plate **30**, and a new pail with clean stones can be put in its place. The top wall **53** of the sump chamber **16** is provided with a cleanout opening which is closed by a hinged cover plate **54**. Beneath this cover plate is a circular drain-plate **55**. This drain plate has holes in it and is supported by the top-wall of the chamber **16**. The cover plate **54** is shown closed in Fig. 2. When a filter unit is removed from the chamber **15**, the cover-plate **54** may be raised and the pail can then be placed on the top of the drain plate, as is the pail **25** in Fig. 3, so that the oil remaining in the pail can drain into the sump and not be wasted.

As already indicated, the filter pieces **27** may be of any suitable material, but are preferably crushed stone. The stones used may be of $\frac{1}{4}$ " to $\frac{5}{8}$ " screening.

It will be noted that in the coolant-circulating system described, the filter unit is on the pressure side of the system. This makes for extended life of a charge of the filter unit, because the pump pressure will force the coolant through the filter when a mere gravity feed would clog. Thus if the filter unit were so positioned as to filter the dirty oil flowing back to the sump by gravity from the wheel and work, the useful life of a given charge of stones would be relatively short for there would not be sufficient pressure to force the dirty oil through the stones after they began to load up with chips and grit.

While the invention has been described in connection with a particular embodiment thereof and a particular use therefor, it will be understood that it is capable of further modification and use. This application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. In a grinding machine having a work support and a grinding wheel, a system for circulating coolant to the point of engagement of the wheel with the work comprising an enclosed

sump, an enclosed filter chamber, an enclosed filter unit in the form of a pail removably mounted in the filter chamber and having openings in one wall thereof which communicate with the filter chamber so that the coolant may flow from said unit into the chamber, said filter unit being of such dimension as to occupy only part of the filter chamber, a pump for pumping coolant out of the sump and through the filter unit into the filter chamber, and piping for conducting the coolant from the filter chamber to the point of engagement of the wheel with the work, and means for conducting the used coolant back to the sump for recirculation by the pump.

2. A coolant circulating system for a grinding machine, particularly for a machine employing oil of relatively high viscosity as a coolant, comprising an enclosed sump chamber for the cool-

ant, a fully enclosed filter chamber separated from the sump chamber, a filter unit removably mounted in the filter chamber and comprising a pail partially filled with irregular shaped insoluble pieces and having openings in its bottom for passage of the coolant therethrough, a pump for pumping the coolant from the sump chamber into the top of said pail, piping for conducting the coolant from the filter chamber to the point of use after the coolant has passed through the filter unit, and means for conducting the coolant after use directly back to the sump chamber, said enclosed sump chamber having drainage openings in its top wall over which a filter pail may be placed, when removed from the filter chamber, to permit drainage back into the sump of the coolant remaining in said pail.

PAUL F. BARKER.
